UNITED STATES PATENT OFFICE.

SIDNEY U. BARR, OF NEW YORK, N. Y.

WINDOW.

No. 879,832.

Specification of Letters Patent.

Patented Feb. 18, 1908.

Application filed March 27, 1907. Serial No. 364,781.

To all whom it may concern:

Be it known that I, SIDNEY U. BARR, a citizen of the United States, and a resident of the city of New York, borough of Brooklyn, in the county of Kings and State of New York, have invented a new and Improved Window, of which the following is a full, clear, and exact description.

The invention relates to windows, such as shown and described in the Letters Patent of the United States, No. 797,835, granted to me on August 2, 1905.

The object of the present invention is to provide a new and improved window which is completely dust proof and air tight, and provided with multiple sashes having interlocking sash stiles, to give the window the appearance of a stationary muntin sash, but the sashes are capable of being opened and closed although no mullions are used.

The invention consists of novel features and parts and combinations of the same, which will be more fully described herein-after and then pointed out in the claims.

25 A practical embodiment of the invention is represented in the accompanying drawings forming a part of this specification, in which similar characters of reference indicate corresponding parts in all the views.

30 Figure 1 is an outer face view of the improvement; Fig. 2 is an enlarged sectional plan view of the same on the line 2—2 of Fig. 1; Fig. 3 is an enlarged cross section of the same on the line 3—3 of Fig. 1; Fig. 4 is a 35 similar view of the same on the line 4—4 of Fig. 1; Fig. 5 is a like view of the same on the line 5—5 of Fig. 1, and Fig. 6 is an enlarged sectional plan of adjacent sashes, one of which is partly open.

40 The sashes A and A' are mounted to swing in the window frame B by the use of hinges or pivots C, C' (see Fig. 2), and the adjacent stiles A², A³ of the said sashes A, A' interlock with each other when the sashes are closed, 45 so that the said interlocked stiles resemble the middle or intermediate bar of a muntin frame window. The inner face of the stile A² is provided with a manually controlled bolt D of the extension or Cremorne type, 50 and adapted to engage the top cross bar B' and the sill B² of the frame B, to securely lock the sashes A and A' in position when closed.

By reference to Figs. 2 and 6, it will be seen that the contacting faces of the interlocking 55 stiles A², A³ are arranged diagonally, and each face consists of a straight middle por-

tion A⁴ and curved side portions A⁵ and A⁶, and the said straight middle portion A⁴ of the stiles A² and A³ are provided with registering grooves A⁷, A⁸ extending throughout the 60 length of the stiles and arranged for the reception of a packing, preferably in the form of rubber tubing E, through which passes a core E' of metal, wood or other material, and screwed or otherwise secured to one of the 65 stiles, as shown in Fig. 6, to the stile A³. Thus when the sashes A, A' are closed the outer portion of the rubber tubing E passes into the groove A⁷ of the stile A² (see Fig. 2), and hence a dust proof and air tight joint is 70 had between the interlocking stiles A², A³.

Similar packings F, F', F² and F³ are arranged between the sash frames and the window frame B, at the bottom, sides and top, but this construction is fully shown and described in the Letters Patent of the United 75 States referred to above, so that further description of the same is not deemed necessary.

The sashes A and A' are provided with fixed cross bars G, G' and intermediate muntin frame bars H, H', and the upper portion of the window is provided with a fixed muntin sash I having intermediate bars I¹, I², I³ in vertical alinement with the interlocking sash stiles A², A³ and the bars H and H', respectively, thus producing a highly ornamental window having the appearance of a fixed muntin frame sash, but being in reality provided with swing sashes.

Although I have shown the parts of the 90 sash frames and window frame of tubular metal, it is evident that I do not limit myself to the use of metal, as wood or other materials may be substituted.

Having thus described my invention, I 95 claim as new and desire to secure by Letters Patent:

A window comprising a mullionless window frame, sashes mounted to swing in the said frame and having their adjacent stiles 100 interlocking when the sashes are closed, the contact face of each interlocking stile having a straight middle portion and curved side portions, and a packing held in recesses formed in the said straight middle portions. 105

In testimony whereof I have signed my name to this specification in the presence of two subscribing witnesses.

SIDNEY U. BARR.
